No. 826,414

PATENTED JULY 17, 1906.

G. FELTZ & W. S. EAST.

SEWER PIPE.

APPLICATION FILED NOV. 18, 1905.

UNITED STATES PATENT OFFICE.

GEORGE FELTZ AND WILLIAM S. EAST, OF LIMA, OHIO.

SEWER-PIPE.

No. 826,414.

Specification of Letters Patent.

Patented July 17, 1906.

Application filed November 18, 1905. Serial No. 288,020.

To all whom it may concern:

Be it known that we, GEORGE FELTZ and WILLIAM S. EAST, citizens of the United States, and residents of Lima, in the county 5 of Allen and State of Ohio, have invented a new and Improved Sewer-Pipe, of which the following is a full, clear, and exact description.

This invention relates to pipes, such as 10 used in the construction of sewers and culverts.

The object of the invention is to produce a 15 pipe of this kind which is simple in construction and arranged so that the succeeding sections interlock with each other.

Further objects of the invention are to prevent scouring under the pipe and to provide 20 improved means for attaching the pipe to a bulkhead, such as found especially in culvert construction.

The invention consists in the construction and combination of parts to be more fully described hereinafter, and definitely set forth 25 in the claims.

Reference is to be had to the accompanying 30 drawings, forming a part of this specification, in which similar characters of reference indicate corresponding parts in all the figures.

Figure 1 is a side elevation showing two 35 connected sections of the pipe and illustrating one of said sections attached to a bulkhead. Fig. 2 is a plan showing the interior of the lower portion of the pipe as represented in Fig. 1, the upper portion of the pipe being 40 represented simply as removed. Fig. 3 is a cross-section on the line 3-3 of Fig. 1. Fig. 4 is a reverse plan showing one extremity of 45 the upper side of a pipe-section; and Fig. 5 is a fragmentary view showing a portion of the 50 wall of a pipe-section and illustrating especially the form of certain lugs, which constitute a feature of the invention.

Referring more particularly to the parts, 1 and 2 represent two connected pipe-sections.

45 The pipe-section 1 represents the usual form of the pipe, while the pipe-section 2 represents a modified construction adopted where a connection is to be made with a flange or bulkhead 3. These pipe-sections 1 and 2 50 are themselves formed in two sections 4 and 5, the lower section 4 being substantially flat below and having diverging upwardly-extending side walls 6. The upper sections 5 1

are substantially semicylindrical in form and constitute domes or caps for the lower sections. The edges of these upper and lower sections come together, as indicated in Fig. 3, and in order to improve the connection we prefer to form one of the edges at each joint with a channel 7, which receives the opposite edge, as shown. The adjacent extremities of the pipe-sections are formed so as to produce an interlocking joint 8, as indicated most clearly in Fig. 2. For this purpose one of the sections, such as the section 2, is provided 55 with a bead or rounded flange 9, and the opposite pipe-section is formed with a groove 10, receiving the aforesaid bead 9, as will be readily understood. By this arrangement the successive sections of the pipe may be 60 jointed together, and, furthermore, each pipe-section is itself composed of two jointed sections meeting in a horizontal line.

The pipe-sections 1 and 2 are further provided with circumferential ribs 11, the purpose of which will appear more fully herein-after.

When attachment is to be made to a flange or bulkhead 3, we prefer to form the bulkhead 3 in two sections 3^a and 3^b, and these sections are divided on a horizontal line 12, which corresponds substantially with the horizontal meeting edges of the upper and lower sections of the pipe, as indicated most clearly in Fig. 3. These bulkhead-sections 3^a and 3^b are 80 adapted to be connected directly together, for which purpose we provide oppositely-disposed lugs 13, through which bolts or rivets 14 pass, as indicated. At suitable points on the outer face of the wall of the pipe-section 85 2, to which the bulkhead is to be attached, we provide a plurality of lugs 15, the form of which is very clearly illustrated in Fig. 5. These lugs are simply knobs or projections having T-slots 16 cut centrally therein and 90 in a longitudinal direction with respect to the axis of the pipe. On the adjacent face of the bulkhead 3 we provide a plurality of arms 17, which correspond in position to the aforesaid lugs 15. These arms are preferably formed 95 with flanges 18, which project on opposite sides thereof and lie against the outer face of the pipe, the said flanges being reinforced by webs 19, as indicated. These webs 19 at suitable points are provided with openings to 100 receive transverse pins 20. It should be un-

derstood that in attaching the pipe-section to the bulkhead these arms 17 are received in the T-slots 16, the webs 19 thereof passing through the contracted part of the slots, as will be readily understood, the flanges 18 being received in the enlarged portions of the slots. After the pipe is attached to the bulkhead the transverse pins 20 are driven in, and the openings of these pins are so located that the pins rest against the sides of the lugs 15 remote from the bulkhead. In this way the pins operate to hold the bulkhead rigidly to the pipe-section.

The flanges having the grooves 10 of the pipe-sections project outwardly from the body of the pipe, as illustrated most clearly in Fig. 2, and these have a tendency to prevent scouring out of the dirt or similar material under the pipe-line. The ribs 11 referred to above have the same general purpose and also tend to prevent the dislodgment of the pipe after being laid. While we prefer to give the grooves 7 the form referred to, these grooves may have any form desired. By forming the pipe-sections with substantially flat bottoms a better support is formed for the same, which tends to prevent sinking of the pipe after being laid, and, furthermore, this form of pipe is conducive to a high efficiency in flow of the current within the same.

With the bulkhead attachment described a liberal amount of expansion and contraction may take place in the pipe-line without materially displacing the bulkhead. This occurs, of course, because there is necessarily a certain amount of play or lost motion at the pins 20.

Having thus described our invention, we claim as new and desire to secure by Letters Patent—

1. A pipe-section having lugs on the outer face thereof, said lugs having slots formed therethrough, and a bulkhead abutting the extremity of said pipe and having arms passing through said slots, and means for retaining said arms in said slots. 45

2. A pipe-section comprising an upper section and a lower section jointed thereto, said pipe-sections having lugs formed on the outer side thereof with transverse slots and a bulkhead abutting the extremity of said pipe-section and having arms passing through said slots and pins passing through said arms and engaging said lugs. 50

3. A pipe-section comprising an upper section and a lower section jointed thereto, a bulkhead formed in sections corresponding to said upper and lower sections and abutting the extremity of said pipe-section, said pipe-section having lugs on the outer side thereof with T-slots therethrough said bulkhead having arms on the inner face thereof projecting through said slots and lying against the outer face of said pipe-section, and pins passing through said arms and engaging the remote sides of said lugs to retain said bulkhead. 55

In testimony whereof we have signed our names to this specification in the presence of two subscribing witnesses.

GEORGE FELTZ.
WILLIAM S. EAST.
